UNITED STATES PATENT OFFICE.

LIBORIUS SENGE, OF CRESCENT SPRINGS, KENTUCKY, ASSIGNOR TO THE GLOBE-WERNICKE COMPANY, OF CINCINNATI, OHIO, A CORPORATION OF OHIO.

ADJUSTABLE SHELF.

1,065,004.

Specification of Letters Patent. Patented June 17, 1913.

Application filed November 30, 1910. Serial No. 594,987.

To all whom it may concern:

Be it known that I, LIBORIUS SENGE, a citizen of the United States, residing at Crescent Springs, in the county of Kenton 5 and State of Kentucky, have invented certain new and useful Improvements in Adjustable Shelves, of which the following is a full, clear, and exact description, reference being had to the accompanying drawing, forming part of this specification.

My invention relates to adjustable shelves for sheet metal cabinets or safes, wherein it is desired to provide an adjustable shelf which does not necessitate the reduction of 15 the available space within the cabinet or safe between shelves, and when placed in any of its adjusted positions can not become changed therefrom by accident, and it has for its object the provision of simple, cheap 20 and efficient mechanism for accomplishing the above purpose.

The novelty of my invention will be hereinafter more fully set forth and specifically pointed out in the claim.

25 In the drawing: Figure 1 is a broken perspective view of a part of a safe showing one of my adjustable shelves in place therein. Fig. 2 is a broken bottom plan view, partly in section, of my adjustable shelf. 30 Fig. 3 is an end view of Fig. 2.

The same numerals of reference are used to indicate identical parts in all the figures.

In its preferred form of construction my shelf consists of the main shelf portion 1 35 composed of sheet metal having its ends rolled over, as at 2, its rear edge rolled over, as at 3, and its front edge rolled over, as at 4. Pins 5—5 are inserted in the rear ends of the openings formed by the rolled over 40 ends 2—2, and these pins 5 project a sufficient distance to support the rear end of the shelf when the same is in place in the safe. Pins 6—6 having handles 7—7 are inserted in the two ends formed by the rolled over 45 front edge 4, the handles 7—7 extending through slots 8—8 in the rolled over portion 4 to permit of manual operation of the pins 6—6. A spring 9 is strung onto the reduced end of each pin 6, and a detent 10, 50 forming an abutment for said spring 9, serves, through the action of said spring, to normally press said pin outward so that it extends beyond the ends of said shelf 1.

A double row of openings 11, one row on each side and arranged vertically is provided in the rear wall 12 of the safe, and a single similar row of openings 13 is provided in the front edge of each side wall 14 of the safe, all of the openings 11 and 13 being arranged in series in such manner that 60 each series is on the same level plane, and the spacing apart of these planes may be equidistant or not according to the use to which the safe is to be put.

To place the shelf in position in the safe 65 the operator grasps the front edge thereof, one end in each hand, and by engaging the handles 7—7 compresses the spring 9—9 thus drawing the pins 6—6 within the area of the shelf 1 and permitting the pins 5—5 70 to engage the openings 11—11 in the rear wall 12 of the safe, upon which engagement, pins 6—6 come opposite openings 13—13, and upon releasing handles 7—7, springs 9—9 become effective to cause engagement 75 pins 6—6 come opposite openings 13—13 thereby securely locking said shelf in position, as will be readily understood. To remove the shelf from the safe the operator simply depresses springs 9—9 through handles 7—7, thereby disengaging pins 6—6 80 from openings 13—13, and by withdrawing the shelf from the safe, disengaging the pins 5—5 from the openings 11—11, whereupon the shelf may be reinserted in another place 85 or left out of the safe as may be preferred.

Having thus fully described my invention I claim—

In an adjustable shelf of the character described, rearwardly extending pins 5 se- 90 curely held in place by means of the rolled over side edges 2 of the shelf, pins 6 provided with operating handles 7, movably attached to said shelf by means of the rolled over front edge 4, said pins 6 being pro- 95 vided with springs 9, serving to normally hold the pins in their extended positions beyond the edges of the shelf, all of said pins being adapted to engage openings in any suitable structure.

LIBORIUS SENGE.
